UNITED STATES PATENT OFFICE.

FREDERICK C. OVERBURY, OF RUTHERFORD, NEW JERSEY, ASSIGNEE TO FLINTKOTE MANUFACTURING COMPANY, OF BOSTON, MASSACHUSETTS, A CORPORATION OF NEW JERSEY.

MACHINE FOR MAKING FABRIC SHINGLES.

1,301,591.

Specification of Letters Patent. Patented Apr. 22, 1919.

Application filed July 14, 1915. Serial No. 39,824.

To all whom it may concern:

Be it known that I, FREDERICK C. OVERBURY, a citizen of the United States, residing in Rutherford, county of Bergen, and State of New Jersey, have invented certain new and useful Improvements in Machines for Making Fabric Shingles, of which the following is a specification.

This invention relates to a machine for making fabric shingles and more particularly to a mechanism for automatically forming shingles of the type in which the exposed edge has a folded portion adapted to underlie the main portion of the shingle and form a securing element thereof.

In shingles of the character referred to, the lower edge of the shingle is connected to the main portion of the shingle by a bend which is formed and set while the fabric and its coating are in a heated or plastic condition. In laying these shingles they are secured to the roofing in overlapping courses with the joints broken in the usual manner. However, in place of driving the nail or other securing member through the main portion of the shingle it is driven through the return bent lower edge portion, the remainder of the shingle being turned back while the nails are driven and the main portion of the shingle then drawn up over the nailed portion giving a double or thickened edge effect to the exposed edge of the shingle. The peculiar manner of securing these shingles to the roofing makes it advisable to provide some means of properly indicating the amount of overlap for each succeeding course and it is among the objects of invention to provide a means for placing on the under side of the shingle guide marks which, when the shingle is bent over into its attached position, will indicate the correct part of the shingle to which the nailing strip on the next shingle shall be secured.

Other salient objects of the invention are to provide a machine by which such shingles can be automatically formed and the bent portion properly stretched and set while in a heated condition; to provide a machine which will perform both the bending operation above described and properly position the holes through which the nails are being driven; to provide means for forming the overlap guide marks preferably simultaneously with the formation of the nail holes;

to provide a construction in which the shingles are automatically marked and bent, thus insuring the shingles being accurately formed without the employment of skilled labor; to provide a construction in which two or more of the shingles can be treated simultaneously and which, when formed, will be automatically conveyed to the packing space, the rolls which set the bends being preferably employed for carrying the shingles away from the forming mechanism; and in general to provide a simple and efficient mechanism by which a plain blank can be rapidly and automatically converted into a complete shingle having the characteristics above mentioned. The invention further resides in various features of construction and combination of parts hereinafter described.

In the drawings:

Figure 1 is a side elevation of a machine embodying my invention.

Fig. 2 is a fragmentary sectional view thereof.

Fig. 3 is an end elevation of the machine shown in Fig. 1.

Fig. 4 is a plan view of the blank.

Fig. 5 is a plan view showing the nail and overlap marks.

Fig. 6 is a cross section through the completed product.

Fig. 7 is a plan view showing the manner of attaching the shingles.

Fig. 8 is a perspective view showing the shingles in use.

Referring in detail to the particular embodiment of my invention shown in the drawings, and describing first the type of shingle manufactured by the machine, 1 designates the blank formed of flexible fabric coated with a bituminous substance or compound, this blank having a main portion 2, and a securing flap 3, the latter being connected to the main portion by an integral bend 4, which forms the lower or exposed edge of the shingle when laid. The flap portion 3 is provided with nail holes 5 and 5', while on the reverse side of the blank and on the opposite side of the bend 4 is a plurality of guide marks 6 and 7, which indicate the amount of overlap that should be allowed in laying the next course of shingles.

For making shingles of the character

above described, I employ a power driven machine 8, which is mounted on a bed plate 9 and has the following mechanical construction: 10 designates the feed bed along 5 which the shingle is fed until its inner end reaches the stop 11. In Fig. 3 it will be noticed that a pair of side guides 12 and 13 are also employed against which the outer edge of each of the sides of the shingle 10 rests, it being understood that a pair of shingles are operated upon simultaneously in the particular machine shown.

When the shingles have been advanced along the feed bed until they abut against 15 the stop 11, they are correctly positioned both laterally and longitudinally relative to the forming mechanism, and the next operation on the blank is the formation of the nail holes and the production of the overlap 20 lap marks on the under side of the sheet after which the blank is bent and removed. All of these operations are performed by mechanism driven from a common driving shaft 14, on which is mounted a large cam 25 wheel 15 having a projecting cam member 16 and an auxiliary cam member 17. The last mentioned cam member during each revolution of the shaft operates upon a roller 18 carried by a swinging arm 19, 30 which in turn is non-rotatively secured to a rock shaft 20. Similarly secured to this shaft is a plurality of rock arms 21, each having at its lower end a hammer member 22, which is positioned directly above but 35 normally spaced from coöperating marking members 23.

The construction is such that when the cam 17, acting on the roller 18, rocks the arm 19 and the shaft 20, the hammer members 22 will be forced downward against the 40 upper surface of the shingle and will press the lower face of such blank onto the marking members 23 and thereby form indentations on the under side of the blank, which 45 indentations will serve as guide marks to show the amount of overlap in laying the next course of shingles. The shaft 20 carries at one end an arm 24 provided at its free end with a stud for engaging the free 50 end of an arm 25 connected to a rock shaft, which carries companion arms linked at their outer ends to a cross shaft 26 carrying nail hole punches 27. Thus, as the lever 21 forces the hammer members down against 55 the shingle blank, it simultaneously forces the nail punches 27 downward to perforate the shingle blank sufficiently to indicate where the nails shall be driven. Each of the nail hole punches 27 is provided with a 60 spring 28, which serves to automatically return the punches to their raised position as soon as the action of the cam member 17 is completed.

Just after the overlap and nail hole marks 65 have been produced on the respective op-

posite sides of the sheet, the cam member 16 moves into engagement with the roller 30 on the free end of a rock arm 31, which is pivoted at 32. This moves the free end of the rock arm 31 upward and thus forces 70 downward the opposite end of this arm 31, which is connected by a link 33 to the sliding head 34, and carries the dull knife or plunger 35. The downward movement of this plunger bends the blank near its inner 75 edge downwardly and carries it into engagement with the rollers 36 and 37, the latter of which is slidably mounted and spring pressed toward the former by a coil spring 38.

For driving the rollers 36 and 37, they are provided with intermeshing gears 40 and 41, the former of which meshes with an intermediate gear 42, which in turn is driven by a large gear wheel 43 mounted 85 upon the shaft 14. Positioned just beneath the rollers 36 and 37 is an auxiliary pair of rollers 44 and 45, the latter being spring pressed toward the roller 44 by the action of a spring 48. These rollers are provided with 90 intermeshing gears 46 and 47, the gear 46 also meshing with the intermediate gear 42. Both sets of rollers are therefore driven from the same power shaft that the marking and bending mechanism is operated by, 95 and all the operations are thus positively actuated in proper sequence.

Positioned at one side of the bed plate 9 is a heating tank 50, the water within which can be heated in any suitable manner such 10 as by the heating coil 51. Before placing the shingles on the feed bed, they are placed in the tank 50 where they are subjected to the action of heat and softened so that the plunger 35 in bending the shingle will not 10 break down the fiber of the fabric or its coating. The shingles after being treated are taken from the tank and advanced along the feed bed until their inner ends abut against the stops 11. The overlap marks 1 and shingle nail holes are then produced as above described and the inner ends of the shingle bent and forced downwardly by the action of the plunger 35 until they are forced intermediate the rollers 36 and 37. These 1 rollers rotating in the direction indicated by the arrows and being spring pressed together will draw the bent end of each of the shingles between them and carry them down until they reach the auxiliary rollers 1 44 and 45, which serve to further press and set the return bend ends or flaps 3 back upon the main portion 2. These last mentioned rollers are also driven in a direction to carry the shingles downward onto the incline 1: 52, from which they are discharged onto the conveyer 53, which conducts them away to the storage or packing space.

A machine such as above described will automatically produce shingles which can be 1

laid with the return bent securing flap positioned under the main portion of the shingle and without danger of the shingle cracking at the bend. Moreover, the formation of 5 the overlap guide marks and the nail hole marks enables the shingles to be rapidly and accurately applied to the roof. While I have shown and described the machine as adapted to produce a particular type of 10 shingle, it is obvious that the use of the machine is not limited to the specific use mentioned and that various changes in construction and combination of parts can be made within the scope of my invention.

15 I claim as my invention:

1. In a machine for making fabric shingles, the combination with means for indicating nail holes in the shingle, means for producing marks on the shingle to indicate 20 the amount of overlap, means for bending back that portion of the shingle in which the nail holes are indicated and a common driving means for said nail hole indicating, overlapping, marking and bending means.
2. In a machine for forming a coated fibrous shingle member, the combination with a feed bed having side guides and a stop member, of means for bending one edge of the shingle blank back upon the main 30 body of the shingle and a heating tank for heating the shingle members preparatory to

treatment from which the shingles are supplied to the feed bed.

3. In a machine for forming a coated fabric roofing member, the combination with 35 supporting means for the member, of means for making marks to indicate the amount of overlap, comprising a plurality of rock arms, each having a hammer member and cam mechanism for actuating said rock arms. 40

4. In a machine for forming a coated fabric roofing member, the combination with a bed frame, of bending members for forcing one edge of the shingle blank back upon itself, hammers for forming indicating 45 marks on the blank, and cam actuated nail punches for cutting on said blank.

5. In a machine for forming a coated fabric shingle member, the combination with a bed frame, of means for bending back one 50 edge of said blank, comprising a solid head member, a plunger carried thereby, and cam actuated links for operating said head.

6. In a machine for forming a coated fabric shingle member, the combination with a 55 bed frame, of means for bending back one edge of said blank, comprising a solid head member, a plunger carried thereby, cam actuated devices for operating said head, and presser rolls for pressing the bent portion.

FREDERICK C. OVERBURY.
